UNITED STATES PATENT OFFICE

JOHN F. JACKSON, OF PAWTUCKET, RHODE ISLAND, ASSIGNOR TO H. & B. AMERICAN MACHINE CO., OF PAWTUCKET, RHODE ISLAND

REVERSIBLE SPINDLE DRIVE FOR SPINNING AND TWISTER FRAMES

Application filed April 30, 1931. Serial No. 533,969.

This invention relates to reversible spindle drives for spinning and twister frames and has for its primary object to provide means wholly automatic by which the slack of the driving tape may be taken up regardless of the direction in which the machine is operating.

Another object of the invention is to provide means whereby one idler pulley responds to the driving force of the tape while the other is actuated to take up any slack which may occur in the tape.

Further objects and advantages of the invention will become apparent as the description proceeds, reference being had to the accompanying drawing; in which:

The figure is an end elevation partly diagrammatic of the device for use in conjunction with the usual spinning frame.

It has heretofore been proposed to provide take-up devices which are actuated by bell-crank levers in connection with the idler pulleys or in weighting the main drive pulley to produce tension throughout the entire strip. Such devices are, of course, operative only in a single direction. It has also been proposed to weight each of the idler pulleys in such a manner as to be independently operative.

The purpose of the present invention is to provide unitary means whereby the structure is greatly simplified and in which the action in each direction is correspondingly the same, since there is a definite co-action between the idler pulleys.

In proceeding in accordance with the present invention a driving pulley 1 is shown which is mounted and actuated in the usual manner. Idler pulleys 2 and 3 are adjustably mounted above the plane of the driving pulley. The idler pulleys 2 and 3 are carried by pulley arms 4 and 5 respectively and may be shifted longitudinally of said pulley and by adjustment of nuts 6 and 7 which extend through slots 8 and 9 of the pulley arms. The idler pulleys 2 and 3 are provided with the usual bearing cradles 10 and 11. Shaft brackets 12 and 13 are provided and have outwardly extending projections 14 and 15 at their lower ends. Stop pins 16 and 17 are

carried by pulley arms 4 and 5 adjacent the projections 14 and 15 and are adapted to engage therewith when the machine is stopped, and under certain operative conditions as later described. The upper portions of the pulley arms 4 and 5 are extended outwardly and are connected by stop pins 18 and 19 to a cross arm 20 which latter carries a weight 21 between its ends. The weight of pulley arms 4 and 5 is supported by shafts 22 and 23 which engage in slotted portions 24 and 25 provided therefor in the respective shaft brackets 12 and 13. It will be seen that since the weight of the respective idler pulley structures is fulcrumed at a point directly above the axis of rotation, the effect of weight 21 is to urge the idler pulleys and their carrying structures toward each other, this being so because the connecting pins of the weight carrying cross bar 20 are spaced a distance from the fulcrum and hence weight 21 imparts a turning movement to the entire idler pulley structure.

In operation, and assuming the direction of rotation of the driving pulley 1 to be in a direction designated by the arrow, pulley 2 becomes the idler pulley by virtue of the tape A running over it and holding the stop pin 16 in engagement with projection 14 of the shaft bracket 12. The other pulley 3 now acts to tension the tape A since the stop 17 is forced away from projection 15 by the action of the weight 21 on the cross bar. It is of course obvious that when the direction of rotation is reversed, pulley 3 will become the idler pulley and pulley 2 will perform the function of the tensioning pulley.

Having described my invention what I claim as new and desire to secure by Letters Patent is:

1. In a device of the class described, a driving pulley, a tape driven by said pulley, a pair of shaft brackets having downwardly inclined slotted portions adjacent their lower ends, outwardly extending projections carried at the outer lower sides of said shaft brackets, a pair of pulley arms carried by said shaft brackets and having portions engaged in the slots of said brackets, said pulley arms having outwardly extended upper

ends and having longitudinal slots, a pair of pulley carrying brackets adjustably connected to said pulley arms by fasteners engaging in said slots, a pair of pulleys carried by said last named brackets and adapted to be driven by said tape, a cross bar pivotally and adjustably connected to the outer end of the outwardly extended ends of said pulley arms, a weight carried by said cross bar whereby the pulleys are urged toward each other, and stop pins carried by said pulley arms and engaging the projections of said shaft brackets to limit the extent of outward motion of said pulley arms to said shaft brackets.

2. In a device of the class described, a driving pulley, a tape driven by said pulley, a pair of shaft brackets having outwardly extending projections adjacent their lower ends, a pair of pulley arms carried by said shaft brackets outward lateral extensions carried by said pulley arms adjacent their upper ends, a pair of pulleys carried by said pulley arms and adapted to be driven by said tape, a cross bar adjustably and pivotally carried by said pulley arms at points adjacent the outer ends of the lateral extensions thereof, a weight carried by said cross bar between its ends whereby the pulleys and pulley arms are urged toward each other, and means carried by the pulley arms to limit the outward motion of said arms relative to said shaft brackets and by engagement with said projections of the shaft brackets.

3. In a device of the class described, a driving pulley, a pair of driven pulleys, a tape trained over said pulleys to drive the same, a pair of shaft brackets, a pair of pulley arms carried by said shaft brackets and carrying said pulleys, a cross bar connected to said pulley arms, a weight carried by said cross bar whereby the pulleys and pulley arms are urged toward each other, and means carried by said pulley arms to engage said shaft brackets whereby the relative motion of the arms to the brackets is limited.

In testimony whereof I have signed my name to this specification.

JOHN F. JACKSON.
